UNITED STATES PATENT OFFICE.

ALLERT R. LOCKE, OF CHICAGO, ILLINOIS.

INSULATOR FOR ARMATURE-CONDUCTORS.

No. 899,059.

Specification of Letters Patent. Patented Sept. 22, 1908.

Application filed December 20, 1907. Serial No. 407,382.

To all whom it may concern:

Be it known that I, ALLERT R. LOCKE, a citizen of the United States, residing at Chicago, in the county of Cook and State of Illinois, have invented certain new and useful Improvements in Insulators for Armature-Conductors, of which the following is a specification.

My invention relates to improvements in 10 insulators for armature conductors.

One of the objects of my invention is to provide a closed insulating hood adapted to partially surround portions of armature conductors that are joined by soldering, whereby 15 the melted solder, due to the abnormal heat of the conductor, may be caught and retained in intimate contact with the joined conductors until it cools.

My insulator is especially adapted to be 20 used for insulating the armature conductors at points where they are riveted and soldered together, especially in that type of armatures where each conductor turn is divided into two sections, and the ends thereof are 25 electrically joined by riveting and soldering at the points of juncture at the rear end of the armature.

The insulator may also be used at the 30 points where the terminals of the armature coils are joined to the respective commutator sections or bars.

In the drawings; Figure 1 is a plan view of a broken away fragment of a group of armature conductors, showing the points where 35 they are joined at the rear end of the armature of a dynamo electric machine. Fig. 2 is a side elevation of same representing a fragment of a longitudinal section of the armature from the core to the periphery at the 40 rear end of the armature. Fig. 3 shows the terminal of a single armature turn with the insulating hood in section. Fig. 4 is a perspective view of the insulating hood.

In all of the views the same reference characters indicate like parts.

In the illustration the armature conductors 10, 11, 12, 13 and 14 are flat bars, each separately insulated by the application of proper insulating material, such as micanite, 50 shown at 16, completely surrounding each bar. Fig. 1 shows a group of five such bars, which are placed with their narrow edges nearest approaching the armature core. Each of said bars are slightly deflected at

their ends and the copper clip 17 is applied to 55 the end of each bar. The lower part of the clip 17 is riveted to the bar as at 18. The upper end of the clip is perforated as at 18' so that the clip may be conveniently riveted to another set of armature conductors or bars 60 respectively, such as 10', 11', 12', 13', and 14'. The last series of conductors each completing an armature coil of a single turn.

When the conductor 10 and coöperating conductor 10' have been laid in position and 65 riveted together they are then soldered or sweat so as to intimately join all confronting contacting surfaces by means of the flowing liquid metal. The remaining terminals of the coil, 10—10', are similarly joined to respective commutator bars. In like manner all of the armature conductors are thus 70 joined or connected. Each joint made as above described, is then covered by means of my improved insulating hood.

20 indicates my insulating hood, molded of insulating material or formed up of micanite, completely closed at its rear and top sides. In Figs. 1 and 2 two of the insulating 75 hoods are shown in position, and in Fig. 3 80 one of such hoods is shown in cross section.

In Fig. 3 it is clearly shown that the upper right hand closed corner of the hood is slightly elevated, gradually increasing in height from the left hand side at a slight 85 angle. The hood 20 entirely incloses the joint over which it is placed.

It frequently happens, on occasions when an armature is over-loaded, the conductors 10, etc., become so over-heated as to melt 90 the solder between the parts of the joint, and the centrifugal action of the armature causes the solder to either fly out of the joint or to leave the same and bridge the insulation between adjoining conductors, thus "short-circuiting" said conductors and increasing 95 the heat of the armature and frequently melting the conductors of the short-circuited coil.

My insulating hood prevents the solder 100 from leaving the joint, being closed in radial direction, or the path the solder would take if it was not restrained and held by the closed hood. Any solder striking the top surface of the hood would by means of the 105 top angular surface be deposited in the rear top part of the hood and there held. This effect prevents the dissipation of the solder

and its application to other conducting parts of the armature, greatly to the damage of such parts.

It will be seen, by reference to Fig. 2, that 5 the insulating hoods 20 are firmly held in place by bands of insulating material, such as 21 and 22, and that retaining bands of wire, 23, which pass entirely around the armature serve to bind them firmly on the 10 clips 17 and thus secured the joints are thereby well, firmly and permanently insulated.

My invention is especially valuable in armatures of a class wherein the ends of the conductors are covered by a jacket, such as 15 inclosed railway motors and in which the conductors are frequently subjected to heavy over-load and other rough usage.

Having thus described my invention, what

I claim and desire to secure by Letters Patent, is;

20

1. An insulating joint-covering, comprising a separable hood of insulating material, forming an integral unbroken structure closed at one side and end.

2. As an article of manufacture, a hood for 25 covering electric joints in armature construction, comprising an integral unbroken molded structure of insulating material open only at one side and end.

In testimony whereof I hereunto set my 30 hand in the presence of two witnesses.

ALBERT R. LOCKE.

In the presence of—

FORÉE BAIN,

MARY F. ALLEN.
